COOLING APPARATUS FOR RECIPROCATING PISTONS

Application filed March 27, 1931, Serial No. 525,764, and in Switzerland June 7, 1930.

This invention relates to cooling apparatus for reciprocating pistons of internal combustion engines and of the kind in which a liquid cooling medium is delivered from a fixed nozzle in the form of a jet parallel to the path of the piston and enters a receiving orifice or pipe carried by the piston or a member secured thereto and communicating with the interior of the piston.

Hitherto, in cooling apparatus of this type, owing to the inertia of the cooling medium which reciprocates with the piston, this cooling medium tends at certain parts of the stroke to flow back through the orifice and thereby cause back pressure on the jet issuing from the nozzle, and the present invention has for its object to provide improved apparatus by which this back pressure will be reduced.

According to this invention the receiving orifice or pipe communicates with the interior of the piston through an intermediate chamber containing air, whereby pressure impulses or surges in the liquid carried in the reciprocating part of the system and tending to cause flow of liquid towards the fixed nozzle are damped and back pressure on the jet thus reduced.

Conveniently the intermediate chamber carries the receiving pipe and is arranged in that part of the system which reciprocates with the piston, while a non-return valve is preferably provided to prevent return flow of the liquid from the interior of the piston back into the chamber.

Two constructions according to the invention are illustrated diagrammatically by way of example in the accompanying drawings as applied to a vertical double acting internal combustion engine.

In these drawings,

Fig. 1 is an end elevation, partly in section of the improved engine,

Fig. 2 is a fragmentary, vertical, sectional detail of Fig. 1.

The engine comprises a cylinder *a*, a water cooled piston *b*, a piston rod *c* and a crosshead *d*. The crosshead is connected to the crankshaft *f* by a connecting rod *e*, and the engine is supported on a frame *g*.

The cooling water supplied through a pipe *h* issues from a nozzle in the form of a jet *i* parallel to the path of the piston and enters a receiving pipe *l* telescopically movable within an outer tube *o* having an overflow or discharge pipe *p*. The pipe *l* is rigidly connected to and communicates with a chamber *m* containing air and carried on the crosshead *d*, this chamber communicating through a non-return valve *n*, a pipe *k* and a passage *x* in the piston rod *c* with the interior of the piston *b*, from which it is discharged in the manner shown in Fig. 2, through a suitable passage *y*.

As the piston *b*, chamber *m* and pipe *l* reciprocate the cooling medium contained in this part of the system tends, during certain parts of the piston stroke, to be carried by its momentum through the pipe *k* and chamber *m* towards the inlet orifice in the pipe *l*. The air in the chamber *m*, however, acts as a cushion to damp out the pressure surges or impulses thus produced so that the intensity of back pressure impulses which would otherwise result on the jet *i* is reduced and consequent loss of cooling medium avoided. The non-return valve *n* serves to prevent the return of liquid from the interior of the piston to the chamber *m* and thus assist the beneficial action of the air in the chamber *m*.

I claim:

1. In an internal combustion engine the combination with a reciprocating piston, of a fixed nozzle adapted to deliver a cooling medium in the form of a jet parallel to the path of the piston, of a jet receiving orifice connected to the piston by a pipe communicating with the interior of the piston and of a chamber containing air in the passage through which the cooling medium flows from the receiving orifice to the piston.

2. In an internal combustion engine the combination with a reciprocating piston, of a fixed nozzle adapted to deliver a cooling medium in the form of a jet parallel to the path of the piston, of a jet receiving orifice connected to the piston by a pipe communicating with the interior of the piston and of a chamber containing air in the passage through which the cooling medium flows from

the receiving orifice to the piston, said air chamber being arranged in a part of the system reciprocating with the piston.

3. In an internal combustion engine the combination with a reciprocating piston, of a fixed nozzle adapted to deliver a cooling medium in the form of a jet parallel to the path of the piston, of a jet receiving orifice connected to the piston by a pipe communicating with the interior of the piston and of a chamber containing air in the passage through which the cooling medium flows from the receiving orifice to the piston, a non-return valve being provided to prevent flow of the liquid from the interior of the piston back into the air chamber.

4. In an internal combustion engine the combination with a reciprocating piston, of a fixed nozzle adapted to deliver a cooling medium in the form of a jet parallel to the path of the piston, of a jet receiving orifice connected to the piston by a pipe communicating with the interior of the piston and of a chamber containing air in the passage through which the cooling medium flows from the receiving orifice to the piston, the receiving orifice being carried by the air chamber.

In testimony whereof I have affixed my signature.
